Patented July 4, 1922.

UNITED STATES PATENT OFFICE.

THOMAS COSON FOLSOM, OF TAMPA, FLORIDA.

RAILWAY SWITCH.

1,421,444.

Specification of Letters Patent.

Patented July 4, 1922.

Application filed January 19, 1922. Serial No. 530,285.

To all whom it may concern:

Be it known that I, THOMAS COSON FOLSOM, a citizen of the United States, and resident of Tampa, county of Hillsborough, 5 Florida, have invented certain new and useful Improvements in Railway Switches, of which the following is a specification.

This invention relates to improvements in the construction of railway switches. One 10 object is to provide a switch of durable construction composed of a minimum number of parts and which is extremely simple in operation.

Another object is to provide a switch 15 which is practically noiseless and so designed that cars going in and out of the switch will ride over the same smoothly with very little jarring and consequently with very little noise.

Another object is to provide a switch 20 with a tongue which can be very readily removed and replaced by the removal of simple securing means.

A further object is to provide a switch 25 having no joint in the tongue of the same.

Other objects will be apparent from the following description when read in connection with the accompanying drawings in which—

Fig. 1 shows a short section of a railway turnout with my improved switch installed therein;

Fig. 2 is a similar view with the switch tongue omitted;

Fig. 3 is a perspective detail of the switch tongue;

Figs. 4 and 5 are sections on lines 4—4, 5—5 of Fig. 2;

Figs. 6 and 7 are sections on the lines 6—6, 40 7—7 of Fig. 1.

Referring more particularly to the drawings, the switch comprises a main base portion 10 shown in detail in Fig. 2, and a tongue shown in Fig. 3. The base portion 45 is formed of either a casting or forging and is joined to the adjacent track sections in any approved or usual manner. Formed on the base is an outer rail portion 12 which extends from one end 14 to the other end 16 of said base, the end 14 being connected for example with a branch track 18 indicated in dotted lines and the end 16 being connected with a straight-away track 20. The base is also provided with a substantially 55 triangular central raised portion 22 against one side 24 of which the tongue of the switch

abuts. The base is further formed with an outer flange 26 and base flanges 28 by which it is secured to the ties in any suitable manner. At its wide end, the base of the switch 60 is formed with a slot 30 arranged to receive the web portion 32 of the tongue 34 of the switch. The web 32 is perforated at 36 and 38 for the reception of bolts 40—40 which extend through suitable holes formed in the 65 body portion of the base of the switch, said bolts being secured in place by suitable nuts 42. The tongue 34 of this switch is of the shape shown in Fig. 3, the rear portion 44 being formed conveniently of a short section 70 of T-rail having flanges 46 and web 32' which is practically an integral continuation of the web 32. The portion of the tongue corresponding to the head or ball of the rail is secured in place so that it forms a continuation of the rail section 19 and its top 75 surface is substantially in alignment to the top surfaces of the portions 12 and 22 of the base of the switch.

The tongue is tapered from the portion 44 80 to its outer end 48 which end fits in a pocket 50 so that the surface 52 of the tongue is substantially in alignment with the surface 54 of the ball portion 12 of the switch base so that the flanges of wheels traveling over the 85 rail will ride over the joint smoothly and easily without jarring and consequently without causing noise. Near the outer end 48 of the tongue a lug 56 is formed through which projects a bolt 58 carrying a spring 90 60 adapted to normally hold the tongue of the switch in the position shown in Fig. 1. Wheels riding over the tongue 24 in the direction of the arrow X will clearly make a 95 smooth exit from the tongue to the portion 12 of the switch without moving the tongue. Wheels traveling over the portion 12 in the direction of the arrow Y will deflect the tongue away from the portion 12 overcoming the tension of the spring 60 and the elasticity 100 in the long tongue section. The end 48 of the tongue is of such small width that the flange of the rail will readily pass the offset of the pocket 50 without causing any appreciable jar and without causing much 105 noise, it being appreciated by those skilled in the art that the side flanges of railway wheels are gently tapered and this taper is greater than the amount of offset of the pocket 50. In a full sized switch the extreme 110 end 48 of the tongue is approximately only 9/64ths of an inch in width and the amount

of offset of the pocket 50 is approximately the same distance so that it will be appreciated that very little jarring or noise will be caused by a tapered flange rolling past 5 this offset.

The switch constructed as above set forth is composed of only two parts, the tongue being made of one solid integral piece, and being rigidly secured at one end by means 10 of the bolts 40 which hold the web of the tongue securely in the slot 30 of the switch base. If desired the tongue can be moved by attaching any approved form of switch-throw device or it can be thrown by the use 15 of a switch rod. The structure is such that the parts can be manufactured at a comparatively small cost, yet the parts are durable and sufficiently strong to stand up under severe service. The tongue is so constructed 20 that it can be readily removed after it has become badly worn and quickly replaced by another one by merely detaching the bolts 40.

Though I have described quite specifically the structural details of the embodiment 25 shown, it is not to be construed that I am limited thereto, as changes in shape and arrangement of the parts may be made by those skilled in the art without departing from the invention as defined in the following 30 claims.

What I claim is:

1. A switch including a supporting base having a slotted seat portion, a tongue having a web engaging the slotted seat portion

of the base and means for detachably securing the tongue to said base. 35

2. A switch including a supporting base having an integral rail portion one end of which connects with one rail section and the other end of which connects with a second rail section, an elongated detachable switch tongue rigidly secured at one end to said supporting base in alignment with a third rail section and being tapered so that its other end merges into alignment with 40 said second rail section, said tongue being adapted to be sprung out of alignment with 45 said second rail section.

3. A switch including a supporting base having a rail portion connecting two rail 50 sections and a tapered tongue secured at one end in alignment with another rail section, said supporting base having a seat for holding one end of the tongue in position and means for detachably securing said tongue 55 in said seat.

4. A switch including a supporting base having a fixed integral rail portion formed thereon, a tongue having a depending web portion at one end, a seat formed in the supporting base, means for rigidly securing said web portion in said seat and yielding means for normally holding the free end of said tongue in contact with the rail portion of the supporting base. 60 65

In witness whereof, I have hereunto signed my name.

THOMAS COSON FOLSOM.
